CLAIM

The ornamental design for a medical apparatus as shown and described.

DESCRIPTION

FIG. 1 is a perspective view of a medical apparatus according to an embodiment showing my new design,

FIG. 2 is a front view thereof,

FIG. 3 is a back view thereof,

FIG. 4 is a left side view thereof,

FIG. 5 is a right side view thereof,

FIG. 6 is a top view thereof,

FIG. 7 is a bottom view thereof,

FIG. 8 is a perspective view of a medical apparatus according to an embodiment showing my new design,

FIG. 9 is a front view thereof,

FIG. 10 is a back view thereof,

FIG. 11 is a left side view thereof,

FIG. 12 is a right side view thereof,

FIG. 13 is a top view thereof; and,

FIG. 14 is a bottom view thereof.

The features shown in broken lines form no part of the claimed design.

1 Claim, 14 Drawing Sheets(56)
